UNITED STATES PATENT OFFICE.

JAMES ROSS, OF SASKATOON, SASKATCHEWAN, CANADA.

COMBINED CHAIR AND HAMMOCK.

1,317,106.

Specification of Letters Patent. Patented Sept. 23, 1919.

Application filed March 31, 1919. Serial No. 286,606.

To all whom it may concern:

Be it known that I, JAMES Ross, a subject of the King of Great Britain, residing at Saskatoon, in the Province of Saskatchewan and Dominion of Canada, have invented new and useful Improvements in Combined Chairs and Hammocks, of which the following is a specification.

This invention relates to a new and useful improvement in a suspension chair and the principal object of the invention is to make the chair similar to a canvas hammock with means for suspending the chair in different positions.

Another object of the invention is to provide means whereby the position of the foot rest of the chair may be adjusted to different positions.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

30 Figure 1 is a side view of the invention; Fig. 2 is a rear view;

Fig. 3 is a section on line 3—3 of Fig. 1; and

Fig. 4 is a detail.

35 As shown in these views I construct the chair from a strip of canvas 1 having one end secured to a cross piece 2 of wood or the like. The other end of the canvas is secured to a foot rest 3 which is also made of wood or similar material and is padded as at 4.

40 The strip 2 is provided with the openings 5 through which the ends of the suspending ropes 6 are passed and knotted. The ends of the ropes are secured to a supporting rim

45 7 which is adapted to engage a hook or the like as usual. I may place fingers 8 on the ropes to engage with the cross piece 2 to give the chair a finished appearance. Clips 9 are secured to the ends of the cross piece 2 and

50 these clips carry the buckles 10. A strip 11 has its ends secured to said buckles and said strip is looped around the edge of the seat portion of the canvas strip 1 and secured thereto by stitching or the like. In this way the canvas strip is held in position to form

55 a seat, a back and a leg supporting part. I

also provide a pair of strips 12 which have their upper portions stitched to the rear side of the back portion of the canvas strip and to the under part of the rear part of the seat portion and from said seat portion the strips extend downwardly and are secured to the under side of the foot rest 3. The foot rest has secured to its outer edge the ropes 13 which are secured to the main rope 14, which carries the rings 15 and 16, the ring 15 being spaced from the ring 16 so that when this ring 15 engages the supporting hook the foot rest will be raised so as to support the occupant of the chair in a reclining position. By placing the ring 16 in engagement with the supporting hook the occupant of the chair will be supported in an upright position.

I form pockets 17 in the sides of the chair as shown, these pockets being formed by sewing an extra strip to the side pieces of the canvas.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A device of the class described, comprising a cloth strip forming the back and seat of the chair, the seat portion having side extensions and strips secured to the side extensions to form pockets, a rigid cross piece connected with the upper end of said strip, flexible strips connecting the front edge of the seat portion with said rigid cross piece, suspending ropes connected with said cross piece, and suspending means connected with the seat portion of the chair.

2. A device of the class described, comprising a canvas strip forming the back and seat portions of the chair, a foot rest connected with the extended portion of the seat part of said strip, a bar connected with the upper end of said strip, a looped strip having its ends connected with the ends of said bar and its looped portion sewed to the edge of the seat portion thereof, suspending ropes connected with said cross bar and suspending ropes connected with the foot rest.

3. A device of the class described, comprising a canvas strip forming the back, a seat and leg-supporting parts of the chair, a cross bar connected with the upper end of

said strip, a foot rest connected with the lower end of said strip, supporting ropes connected with said supporting bar, supporting ropes connected with the foot rest, a strip 5 having its center stitched to the chair portion of the strip and its ends connected with the ends of the cross bar and other strips

having their portions sewed to the rear face of the back portion and the bottom of the seat portion and their other ends connected 10 with the foot rest.

In testimony whereof I affix my signature.

JAMES ROSS.
